UNITED STATES PATENT OFFICE.

JACOB E. NEAHR, OF NEW YORK, N. Y.

MATCH-SAFE.

1,334,961.

Specification of Letters Patent. Patented Mar. 30, 1920.

Application filed December 21, 1917. Serial No. 208,222.

To all whom it may concern:

Be it known that I, JACOB E. NEAHR, a citizen of the United States, residing in the city, county, and State of New York, have 5 invented certain new and useful Improvements in Match-Safes, of which the following is a specification.

This invention relates to match safes and appurtenances, and certain features there- 10 of are in the nature of an improvement over the structure disclosed in my Patent No. 1,144,612 of June 29, 1915, in which a coil of ignition strip is carried in a drum, and the end of the coil is led out through an 15 aperture and wrapped around the drum and secured.

One feature of the present improvements relates to a provision for insuring that the coil of strip shall be properly placed in the 20 drum, so that it will emerge through the aperture with its right side out, for wrapping around the drum in the proper direction. To this end, the coil is mounted upon a core, which may be made of wood or other 25 material, said core having a special structure, and there being placed in the drum a special support, so that the core cannot be set wrong upon said support, and hence the coil when inserted in the drum must always be 30 right side up, avoiding liability of the coil emerging from the aperture with the wrong side out. Moreover, the structure whereby this result is secured is also useful in preventing substitution of spurious coils in the 35 drum.

Another feature of the invention relates to the device upon which the match-striking drum and safe are mounted. Said device comprises a tray or dished receptacle for 40 burnt matches, cigar ends, ashes, and so forth. The pedestal for carrying the match safe rises from said tray, preferably from the middle thereof; and said tray in turn is utilized as a lid or removable cover for a relatively 45 large receptacle, which forms the base of the entire article. Said receptacle has at its top a very large opening, which may be of circular contour, of a diameter about equal to that of the aforesaid tray. In 50 order to clean out the tray, it is only necessary to lift the same (using the match safe as a handle) and tip the contents of the tray right into the base receptacle, then replacing the tray in position to serve as a lid. 55 The appearance of the tray and cover is harmonious, the dishing of the tray lend-

ing attractiveness to the entire base, as well as serving to render the tray adaptable as a temporary receiver for ashes, etc. It will be understood, however, that the base and ash tray may be employed in connection with other forms of match safes or match-striking devices.

The device has the further advantage that the tray with its match safe may, if desired, 65 be used separately from the base, and can be supplied separately from the tray to be re-tailed either with or without the base; the tray itself being of sufficiently broad dimensions to serve as a base, if required, and 70 forming a complete article of commerce capable of independent use as an ash tray separately from said receptacle.

Other features and advantages will hereinafter appear.

In the accompanying drawings,

Figure 1 is a perspective view, showing the tray tilted to dump its contents into the base receptacle.

Fig. 2 is a plan, showing the mounting of 80 the coil of ignition strip.

Fig. 3 is a sectional central elevation of the device.

Fig. 4 is an enlarged sectional perspective, showing the structure of the core of the coil. 85

As in said patent, the matches are placed in a receptacle 10, which surmounts a drum 11 in which is contained a coil of ignition strip 12, and the coil is led out through an aperture 13 in the drum and wrapped 90 around the same at 14 and then secured by means of a clip 15. In the present instance, the coil is carried upon a core 16, which is centrally perforated at 17 for mounting rotatively in the drum; and the match safe has 95 projecting downwardly from its bottom 18 a central shank or stem 19, which passes down through the central aperture in the core and at its lower end is threaded down into a post 20 which rises from the pedestal 100 21 of the device; said pedestal rising preferably from the central portion of a tray 22.

It will be seen that said post 20 is of considerably larger diameter than the shank 19, and that the strip core 16 has a correspondingly larger counterbore 23 at its bottom. In other words, the hole in the spool is larger at its bottom end than at its top end, and hence the spool cannot be placed upside down upon said post 20. The shank 110 19 may serve as a spindle upon which the core is loosely mounted. The post 20 rises

within the drum and the coil may occupy the entire height of the drum, so that only a core having a proper construction of hole therein can be successfully placed within 5 the drum.

Since the coil is necessarily inserted the right side up, the end may be led out through an aperture and wrapped around the drum in the manner shown in Fig. 2, without the 10 liability of the ignition side of the strip being accidentally placed inwardly against the exterior surface of the drum; thus avoiding difficulty. In order that the spool may rotate freely, the stem of the screw, which is 15 of small diameter, may serve as a spindle for the spool; and the counterbore may be of substantial size, so as not to contact with the post. Thus a great contrast is made between the holes at the opposite sides of the 20 core.

The post may have a shoulder 24 to clamp the bottom of the drum down upon a washer 25 inserted between the drum 11 and the top of the pedestal 21; the post terminating in a 25 rivet head 26, which holds the whole device to the pedestal; and the latter may be of sheet metal and spun or drawn up in the center of the tray, as illustrated.

The tray 22 may be of relatively great 30 diameter and of dished form as shown, so as to have a great utility as a temporary receptacle for ashes and the like; and at its elevated border or edge it may be rolled over to form a bead 27 to overhang the edge 35 of the large opening in the top of the base, which may comprise a flat bottom or floor 28 and a side wall 29. The upper edge of the wall may be formed with an interior flange 30 to conduce to security and stiffness; the bottom of the side wall being held 40 in place by a flange 31 spun up from the floor.

The capacity of the base receptacle is 45 preferably several times greater than the capacity of the tray, so that the tray may be repeatedly cleared of debris before it becomes necessary to clean out the base receptacle. This is a convenience where many of the articles are in use, as the attendant or 50 waiter can readily clear out any tray as soon as anything is deposited therein, and without waiting for further accumulation; and he can do this without taking the article away from the table. Hence, the trays may easily 55 be maintained practically in clean condition throughout the day and evening, rendering it unnecessary to clear out the base except more than once a day, or even at greater intervals.

60 Variations may be resorted to within the scope of the invention, and portions of the improvements may be used without others.

Having thus described my invention, I claim:

65 1. In a match safe, the combination of a

drum having a central post and a removable top, a central screw having a shank pendent from said top and threaded at its lower end into said post, whereby said top is secured to the drum, said post being of larger diameter 70 than said shank of the screw, and an ignition-strip coil having a core bored to rotate upon said shank of the screw and having its bottom counterbored to accommodate said post.

2. In a match safe, the combination of a drum having a central post and a removable top, a central screw having a shank pendent from said top and threaded at its lower end into said post, whereby said top is secured to 80 the drum, said post being of larger diameter than said shank of the screw, and an ignition-strip coil having a core bored to rotate upon said shank of the screw and having its bottom counterbored to accommodate 85 said post; said drum having an aperture through which an end of the strip is led and wrapped around the drum, and having means to clip the end of the strip.

3. In a match safe, the combination with 90 a drum having a removable top, of a central member comprising a post and also comprising a shank pendent from said top and threaded into said post, whereby said top is secured to the drum, said post and shank 95 being of unequal diameters, and an ignition strip coil having a core bored and counterbored to adapt the core to turn upon said central member; said drum having an aperture through which an end of the strip is 100 led and wrapped around the drum.

4. A combined match-safe, ash-tray and ash-receiver comprising, in combination, a hollow base forming a receptacle for ashes and other refuse, an ash-tray forming a 105 removable cover for said receptacle, and a match-safe mounted on said tray, the contacting surfaces between said base and said 110 cover being so related as to provide a firm support for said tray.

5. A combined match-safe, ash-tray and ash-receiver comprising, in combination, a hollow base forming a receptacle for ashes and other refuse, an ash-tray forming a removable cover for said receptacle, a match-safe mounted on said tray, and a match-striking surface on said safe, the contacting surfaces between said base and said cover being so related as to provide a firm support for 115 said tray, and prevent relative movement between said tray and its base, as a result of the pressure of a match against any portion of said surface.

6. A combined match-safe, ash-tray and ash-receiver comprising, in combination, a 125 hollow base forming a receptacle for ashes and other refuse, an ash-tray forming a removable cover for said receptacle, a match-safe mounted on said tray, and a match-striking surface surrounding said safe, the 130

contacting surfaces between said base and said cover being so related as to provide a firm support for said tray, and to oppose lateral movement between said tray and said base during the striking of a match on any part of said surface.

7. A combined match-safe, ash-tray and ash-receiver comprising, in combination, a hollow base forming a receptacle for ashes and other refuse, an ash-tray forming a removable cover for said receptacle, a match-safe mounted on said tray, and a match-striking surface surrounding said safe, the contacting surfaces between said base and said cover comprising interfitting parts, including a bead on one and a flange on the other, thus providing a firm support for said tray and furnishing means to prevent lateral movement between said tray and said base during the striking of a match against any part of said surface.

8. A combined match-safe, ash-tray and ash-receiver comprising, in combination, a hollow base forming a receptacle for ashes

and other refuse, a dished cover for said base forming an ash-tray, and a match-safe mounted on said tray, said hollow base affording space for the dished portion of said tray, and the contacting surfaces between said base and said tray affording a firm tray support.

9. A combined match-safe, ash-tray and ash-receiver comprising, in combination, a hollow base forming a receptacle for ashes and other refuse, an ash-tray forming a removable cover for said receptacle, and a match-safe mounted on said tray, said safe and cover forming a complete match-safe and ash-tray adapted for use independent of said base, and said base and said tray being so related one to the other that the former may serve as a firm support for the latter when the tray is used as a cover for the receptacle.
